UNITED STATES PATENT OFFICE

HAROLD ARTHUR CROCKER, OF LONDON, ENGLAND, ASSIGNOR TO J. STONE & COMPANY LIMITED, OF DEPTFORD, ENGLAND, A CORPORATION OF GREAT BRITAIN

SIDE-LIGHT, SIDE-SCUTTLE OR PORT OPENING FOR SHIPS

Application filed June 27, 1931, Serial No. 547,399, and in Great Britain December 5, 1930.

This invention comprises improvements in and connected with side-lights, side-scuttles or port openings for ships and is concerned with that type of apparatus in which the closure, usually a glazed sash, is mounted to 5 swivel upon trunnions or diametral pivots so that it can be readily opened, but is, nevertheless, capable of being pressed strongly against a seating to ensure water-tightness in 10 the closed condition. Before such a closure or sash can be swivelled to an open position, it must be moved bodily a certain distance away from the seating so that its approaching arc will clear the port opening during the 15 swivelling movement. The principal object of this invention is to construct a side-light or scuttle of this character of very few parts so as to attain simplicity of design and economy in production and, moreover, to 20 devise those parts so that the operation is easy but very reliable in effect.

These improvements are equally applicable to circular and oval or elliptical side-lights and are advantageously adapted so that the closure or sash moves inwardly against its seating, whereby external pressure of wave or wind tends to increase the water-tightness of the closed condition.

According to this invention, the trunnions or diametral pivots of the closure or sash, which are movable in guides perpendicular to the plane of the seating, are adjusted in those guides by engagement with cams or revoluble means on the framing in order to 30 adjust the closure or sash from or towards its seating. These cam devices or revoluble means alone may produce the strong pressing of a sash against its seating in the closed condition, but the possibility of using auxiliary 35 means for this purpose is not excluded.

To enable the invention to be readily understood, reference is made to the accompanying drawings illustrating, by way of example, one construction embodying the present improvements, in which drawings:—

Figure 1 is an elevation as seen from the inner side of a port opening.

Figure 2 is a central vertical section of 50 Figure 1.

Figure 3 is an inverted plan of the bottom part of Figure 1.

Figure 4 is a view similar to Figure 1, but showing a dead light or cover fixed over the port opening.

Figure 5 is a cross section on the line V—V of Figure 4.

Figure 6 is a sectional perspective view illustrating clearly the operative parts seen at the bottom of Figures 1 and 2.

Figure 7 is a sectional view of an auxiliary clip device or fastening for the sash.

Figure 8 is an elevation of the clip device as viewed from the right hand side of Figure 7.

In the example illustrated in the drawing, the framing *a* is cylindrical with a flange *b* at one end for fixing to a support which may be the skin of a ship. At the other or inner end, the cylindrical frame is formed or fitted with an inner grooved ring or rim *c*, the groove having inserted into it a suitable seating ring, such as rubber ring *d*. At diametrically opposite points, as at the top and bottom of the vertical diameter, the cylindrical frame is formed with slots *e* parallel with its central axis. At the said points, the framing *a* is formed with flats or bosses *f* extending on either side of each slot, and a cover or box *g* is fastened, as by screws, against each of these flats. Each cover or box *g* is recessed to receive a disc or cam *h* the recess being elongated so that its sides *g'* Figures 2 and 6, serve as a guide for the disc or cam *h*. Moreover, each cover or box *g* is formed with a slot *g*² to serve as a guide for a stub *j* on which said disc or cam *h* is fixed or formed. The slot *g*² in each cover or box *g* extends at right angles to the adjacent slot *e* in the frame *a*, as seen in Figure 3. The sash ring *k* for the circular light *l* is fitted at diametrically opposite points with pivot pins or trunnions *m m'* which are slidably engaged in the slots *e* of the cylindrical frame *a* when the sash *k* is inserted into the frame *a*. Each pivot pin extends through its appropriate slot *e* in the framing and such extension is engaged in a perforation of its respective cam or disc *h* disposed externally of the slotted part of the framing. The stubs *j* of the discs or

90

100

cams h extend through the guide slots g^2 in the box or cover g to a sufficient extent for the engagement therewith of the hubs n of an operating handle o and for the reception of fixing nuts p . The operating handle o is advantageously a semi-circular bail, as seen in Figure 1, formed with a radius greater than that of the circular light and having at the ends the hubs n adapted for engagement with the stubs j as aforesaid. Let it be assumed that the circular sash k is hard against its seating d in the frame a and that in this condition the operating handle o lies in a plane parallel with that of the sash k , as illustrated in Figures 1 to 3. The trunnions or pivots m m' are then at the inner ends of the slots e in the frame and, as regards their engagement with the discs or cams h , may be regarded as crank pins on, or about on, a dead centre. When it is desired to open the sash, the operating handle o is swung through an angle of 180° . This causes the discs or cams h to revolve through a like angle but as such discs or cams are engaged with the pivot pins or trunnions m m' which can only move rectilinearly along the slots e in the cylindrical frame, the said discs or cams h move along the guides g' in the boxes or covers g at right angles to the slots e in the frame, their stubs moving along the slots g^2 in the boxes or covers g . The reaction between the discs h and the pivot pins or trunnions m m' causes the latter to move outwardly in the slots e of the cylindrical frame a so that the sash k is moved bodily away from its seating d to such a distance as will enable the sash k to be swivelled about the pivot pins or trunnions m m' to an open position. If it is desired to secure the sash k in a partly open position, as when it has been swivelled to an angle of less than 90° to the plane of its seating d , the operating handle o can be reversely operated through a small angle so as to cause the sash or glass holder k to wedge itself, as it were, against points in the circular aperture or port opening of the frame a . To re-seat the sash k in the tightly closed condition, the sash is swivelled into a plane parallel with its seating d and the operating handle o is swung back to the original position shown in Figures 1 to 3.

To enable the parts to be readily assembled, the trunnion m' may be a stud which is inserted through the sash ring k from the interior thereof and screwed into such ring, the projecting shank portion serving as pivot as seen clearly in Figures 2 and 6. The other trunnion m may be a stud screwed into the sash ring k from the exterior, see Figure 2, and so that the head of such stud remains projecting to serve as the trunnion or pivot pin. By removing the appropriate box or cover g , it is possible to get at the stud m and after removal of such stud, and removal or disengagement of the disc h associated with the

other stud m' , the sash k is removable from the framing a with the said other stud m' intact.

Provision can be made for fitting to the sidelight a portable watertight deadlight q , Figures 4 and 5, by forming a lip or bead r on the inner surface of the fixed frame a and two wedge lugs s on its outer diameter. The deadlight q has a spigot t to locate its position in the fixed frame, two projecting wedges u on its outer diameter to engage with the wedge lugs of the fixed frame, and a rubber jointing ring v for engagement with the bead r .

On sidelights of exceptional size, when it may be considered unsuitable that the application of pressure should be applied to two pivot pins only for forcing the glass holder into the rubber seating ring, additional pressure may be applied through two swing fastenings, as illustrated in Figures 7 and 8. For example, at two diametrically opposite points on the sash ring k lugs w may be formed and adapted for engagement by pivoted hooks or catches x . The latter are pivotally supported by links y pivotally mounted on the frame a , each link having a screw threaded hole to receive a thumb screw z . It will be seen that when the catches x are engaged with the lugs w , the screwing in of the screws z brings their inner ends hard against the rim c of the frame a , so that further screwing forces the links y away from the rim c whereby the hooks x are caused to pull the sash k strongly against its seating d .

As stated above these swing fastenings may be considered desirable in some cases, but as the rubber seating ring d is on the inboard side of the sash or glass holder k , any pressure from water striking the glass l only tends to increase water-tightness, so that additional pressure means, such as the devices shown in Figures 7 and 8, may generally be dispensed with.

In side lights in accordance with these improvements, it is possible to reglaze a glass holder k whilst the latter remains in position in the main frame a .

From Figures 1 to 3 and 6, it will be seen that the hubs n of the handle o are of larger diameter than the discs h and that each of such hubs n is fitted near its periphery with a metallic joint ring n' for bearing against the outer surface of a respective box or cover g . The inner diameter of this joint ring n' is such that the slots g^2 lie within the ring n' at all times and throughout the range of operation of the handle o from the closed to the full open position. Thus, the joint rings n' will always prevent water or other matter from entering the ship through the slots g^2 .

I claim:

1. Swivelling ships-light comprising a frame, a sash, diametral pivots on said sash, pivot-guides in the frame and perpendicular

to the plane thereof, and cam-means for adjusting the sash in the guides from or towards the frame and consisting of rotatable plates slideable transversely in the frame and having the diametral sash pivots journaled therein.

2. Swivelling ships-light comprising a frame, a sash, diametral pivots on said sash, rotatable cam plates in which said pivots are mounted, pivot-guides in the frame and perpendicular thereto, transverse guides in the frame for the cam plates, and manipulating means for rotating said cam plates and thereby adjusting said sash in the pivot guides by virtue of combined rotatory and transverse sliding movement of the cam plates.

3. Swivelling ships-light comprising a cylindrical frame, a round glazed sash, a resilient seating-ring mounted at the inner end of said frame, diametral trunnions on the sash, guide grooves provided for the trunnions in the frame and arranged perpendicular to the seating, round cam plates in which the trunnions are journaled, transverse guides provided for the cam plates at diametral points in the frame, and manipulating means for rotating the cam plates and thereby adjusting the sash inwardly towards or outwardly away from the seating, said means passing through the frame by way of transverse slots therein which permit of transverse sliding movement of the cam plates.

4. Swivelling ships-light comprising a frame for a sash having diametral trunnions, rotatable cam plates adapted for having the trunnions journaled therein, pivot guides in the frame and perpendicular to the plane thereof, transverse guides in the frame for the cam plates, manipulating means for rotating said cam plates, a bead at the inner end of the frame, a deadlight having a resilient seating ring for engaging said bead and interengageable wedge-shaped lugs on the frame and dead light for securing the latter in the former.

5. Swivelling ships-light as claimed in claim 3 and provided with auxiliary fastening means for clamping the sash to the frame at points between the diametral trunnions, comprising hooks engageable with the sash, pivotal mountings for said hooks on the inside of the frame, and manipulating means, such as screws for applying a clamping force to said hooks through their pivotal mountings.

6. Swivelling ships-light comprising, a frame, a sash, diametral pivots on said sash, rotatable cam plates in which said pivots are rotatably mounted, pivot-guides in the frame and perpendicular to the plane thereof, guides for the cam plates, the latter guides being disposed on the frame at right angles to the former guides, and a manipulating handle in the form of a bail for rotating said

cam plates and thereby adjusting said sash in the pivot guides by virtue of combined rotatory and transverse sliding movement of the cam plates.

7. Swivelling ships-light comprising, a frame, a sash, diametral pivots on said sash, pivot-guides in the frame and perpendicular to the plane thereof, cam means for adjusting the sash in the guides from or towards the frame and consisting of rotatable plates slideable transversely of the frame and having the diametral sash pivots journaled therein, and auxiliary sash securing means for clamping the sash to the frame at points between the diametral pivots.
